(57) **CLAIM**

The ornamental design for a roll formed interlocking roofing pan as shown and described.

DESCRIPTION

FIG. 1 is a perspective view of a roll formed interlocking roofing pan showing our new design;

FIG. 2 is an end elevation view thereof, showing the roll formed interlocking roofing pan in an environment of use;

FIG. 3 is a top plan view of the roll formed interlocking roofing pan in FIG. 1;

FIG. 4 is a front elevation view thereof;

FIG. 5 is a left end elevation view thereof;

FIG. 6 is a bottom plan view thereof;

FIG. 7 is a rear elevation view thereof; and,

FIG. 8 is a right end elevation view of the invention.

The broken lines in FIG. 2 represent environmental subject matter only and form no part of the claimed design.

The roll formed interlocking roofing pan is shown with a symbolic break in its length. The appearance of any portion of the roll formed interlocking roofing pan between the break lines forms no part of the claimed design.
